BY

UNITED STATES PATENT OFFICE.

SETH FREDERIC LOW, OF SALEM, MASSACHUSETTS.

DESIGN FOR A SPOON, &c.

SPECIFICATION forming part of Design No. 20,978, dated August 11, 1891.

Application filed May 6, 1891. Serial No. 391,819. Term of patent 7 years.

To all whom it may concern:

Be it known that I, SETH FREDERIC LOW, of Salem, in the county of Essex and State of Massachusetts, have invented and produced 5 a new and original Design for Spoons, Forks, and other Articles in Silver, of which the following is a specification.

Reference is to be had to the accompanying drawing, forming a part of this specification, 10 in which the figure represents a face view of a spoon embodying my new design.

The design embodies symbols and figures commemorative and mindful of the reputed discovery of America by one Leif Ericson, a 15 Norseman.

The features of my design reside in the ornamentation of the handle.

In the accompanying illustration, the handle A of the spoon, as indicated by the letter 20 a, conforms in the main to the configuration of the oars used by Norsemen at the period in which Leif Ericson lived. The surface of the oar appears ornamented with scroll-work.

The letter a' indicates the inner end of the

handle A, the same being fashioned to represent the handle of the oar and ornamented. At the juncture of the handle A and the bowl B of the spoon appears the figure c, representing a bunch of grapes, the same being symbolical of the finding of grapes at the 30 points touched by the discoverer. At the outer end of the handle is the figure of Leif Ericson, (indicated by the letter a²;) the same being a miniature statuette and forming a continuation of the handle, the figure being 35 represented as if peering afar, one hand being raised to the forehead. In the bowl B of the spoon appears the representation of a Norse ship as seen in side view, (indicated by the letter b;) but this forms no part of the 40 design.

I claim—

The design for the handles of spoons and similar ware, as shown and described.

SETH FREDERIC LOW.
